Primary Examiner — Cynthia M Chin(74) *Attorney, Agent, or Firm* — RG Patent Consulting LLC(57) **CLAIM**

I claim the ornamental design for a combined ATV and jet ski, as shown and described.

DESCRIPTION

FIG. 1 is a front, top and side perspective view of the combined ATV and jet ski embodying the design of the present invention.

FIG. 2 is a side elevational view thereof, the side opposite to the side shown in FIG. 2 being a mirror image thereof.

FIG. 3 is a top plan view thereof.

FIG. 4 is a bottom plan view thereof.

FIG. 5 is a front elevational view thereof; and,

FIG. 6 is a rear elevational view thereof.

The broken lines represent portions of the article that form no part of the claim.
